ATTORNEYS

UNITED STATES PATENT OFFICE.

EDMOND J. FORTIER, OF KANKAKEE, ILLINOIS.

AUTOMATIC VALVE.

1,427,098.

Specification of Letters Patent. Patented Aug. 29, 1922.

Application filed June 17, 1920, Serial No. 389,654. Renewed February 10, 1922. Serial No. 535,611.

To all whom it may concern:

Be it known that I, EDMOND J. FORTIER, a citizen of the United States, and a resident of Kankakee, in the county of Kankakee and State of Illinois, have invented a new and useful Improvement in Automatic Valves, of which the following is a full, clear, and exact description.

My invention relates to improvements in automatic valves, and it consists in the combinations, constructions, and arrangements herein described and claimed.

An object of my invention is to provide an automatic valve for a drain pipe or the like in a water system which will be opened by the suction created by the rush of waste water down the drain pipe, thereby preventing syphoning of the liquid seal from the trap in the water system without the necessity of providing a ventilating pipe.

A further object of my invention is to provide a device of the type described that will automatically close when the waste water has ceased to flow down the drain pipe and which will normally remain closed to prevent the passage of gas from the drain pipe therethrough.

A further object of my invention is to provide a device of the type described that can be applied to a drain pipe such as is ordinarily installed without the necessity of making extensive changes in the latter.

A further object of my invention is to provide a device of the type described that is relatively simple in construction and operation, not likely to get out of order easily and thoroughly practical commercially.

Other objects and advantages will appear in the following specification, and the novel features of the invention will be particularly pointed out in the appended claims.

My invention is illustrated in the accompanying drawings, forming part of this application, in which—

Figure 1 is a vertical sectional view through the walls of a room showing the use and application of the automatic valve,

Figure 2 is a side elevation of the device partly broken away and in section, showing the same applied to the drain pipe,

Figure 3 is a section along the line 3—3 of Figure 2,

Figure 4 is a section along the line 4—4 of Figure 3,

Figure 5 is a view of a modified form of the device.

Referring now to Figure 1, 1 denotes the floor of a room and 2, a wall thereof. A sink, or the like, 3, having a basin 5 is supported by a stanchion 4 in an ordinary manner. A drain pipe 6 leads from the bowl or basin 5 through a trap 7, a vertically disposed connecting pipe 8, an elbow 10, and a horizontally disposed connecting pipe 9 to the drain or waste pipe 12. The junction of the horizontally disposed connecting pipe 9 with the waste pipe 12 is effected by means of a pipe fitting, such as a T 11. The parts shown so far are ordinary in construction and form no part of my invention except in so far as they co-operate with the parts to be described.

It has been necessary prior to my invention to provide a ventilating pipe (not shown) which was connected to the pipe 13 and extended upwardly through the roof of a house. The ventilating pipe was necessary, since the rush of the waste water down the waste pipe 12 creates a suction which would otherwise draw the water seal from the trap 7. Consequently, the foul and poisonous gases from the sewer would pass into the room to the detriment of the occupants of the house. When a ventilating pipe is provided, the atmospheric pressure would force air down the latter into the waste pipe 12 when suction was created by the flow of waste water therethrough and would prevent syphoning of the water seal from the trap 7. However, it has been necessary to provide numerous lengths of pipe to extend to the roof and as such pipe had no other function than that stated, the provision of a ventilating pipe entailed considerable cost.

Furthermore, poisonous gases from the waste pipe escaped through the ventilating pipe and contaminated the air, frequently spreading disease in the neighborhood.

In carrying out my invention, I secure the automatic valve to the waste pipe 12 adjacent the junction thereof with the pipe 9 by means of a short pipe 13 and an elbow 14. The valve may be positioned in the interior of the room between the trap 7 and the waste pipe 12, and when so positioned would be connected with the pipe 9, which would be tapped for the purpose.

The automatic valve comprises an outer casing 15, which has its inner end screw threaded exteriorly for engagement with the elbow 14. Within the outer casing 15,

I insert an inner casing 16 which tapers from its outer end to its inner end, as shown. The inner casing 16 has its inner end elevated by means of a lug 18 (see Fig. 5 4) and is maintained in position by diametrically opposed side lugs 17. The outer end of the inner casing 16 is open and is provided with a flange 30 which abuts against the outer end of the outer casing 15 when 10 the inner casing has been inserted within the latter to the desired position. The inner end of the inner casing 16 is partly closed by a disk 19 which is centrally spaced from the walls thereof by means of lugs 20, 15 thereby providing passages 21 for air to pass from the inner casing to the waste pipe 12. An inwardly extending tubular centrally disposed socket 22 is adapted to receive a bumper 23 which is of any suitable 20 material, such as cork, rubber, or the like. A central opening 24 is provided through the disk 19 for convenience in removing the bumper 23 from its socket.

A ball valve 25 is placed within the inner 25 casing 16. A valve seat 28, which may be formed of rubber or any other suitable material is clamped in place against the flanged end of the inner casing 16 by means of a cap 26, which is screwed on the outer casing 30 15. The valve seat 28 is formed with an opening 29 whose inner walls are curved to conform with the shape of the ball valve. An opening 27 is provided in the cap 26 for admission of air. The ball valve 25 in its 35 closed position may project slightly through the opening 27. A plurality of openings 31 are provided in the bottom wall of the inner casing 16, as best seen in Fig. 3. These openings are covered by the ball valve 25 40 when the latter is in its closed position and provide a means for draining the inner casing 15 should any moisture accumulate therein. The outer end of the outer casing 15 is slightly higher than the inner end and 45 any moisture passing from the inner casing 16 through the openings 31 to the outer casing 15 will drain into the waste pipe 12.

Referring now to Figure 5, it will be noted that I may provide an elbow member 50 for covering the end of the outer casing 15 to prevent dust and the like being drawn into the inner casing 16. The elbow member 32 is secured to the outer casing 15 in any suitable manner as by means of a pipe 55 fitting 33.

From the foregoing description of the various parts of the device, the operation thereof may be readily understood. Waste water passes from the bowl or basin 5 into 60 and down the waste or drain pipe 12. The suction created by the rush of waste water together with the normal atmospheric pressure forces the ball valve 25 inwardly against the force of gravity since the bottom wall of the inner casing 16 is inclined, 65

thereby permitting air to flow through the opening 29 into the inner casing 16. Thence the air passes through the apertures 21 into and down the waste pipe 12, thereby relieving the suction on the water seal in the trap 7 and preventing the syphoning of the same 70 therefrom. When the flow of water down the waste pipe has ceased and the inrush of air has overcome the suction created, and filled the waste pipe, the ball valve 25 will 75 roll down the incline into the position indicated by the dotted lines in Fig. 3 of the accompanying drawings. Admission of further air will be prevented. Escape of 80 air from the drain pipe 12 is also prevented and consequently poisonous sewer gases cannot pass through the drain pipe and therefrom.

The use of my improved automatic valve results in a great saving in cost when a water system is being installed since it is not necessary to provide the ventilating pipe as was formerly necessary. Furthermore, the health of the occupants of a building in which the water system is installed is safeguarded, since a positive check is placed on the poisonous sewer gases which are prevented from passing up the waste pipe 12. It is obvious that many modifications and 90 adaptations of the form of the device pictured in the drawings may be provided without departing from the spirit and scope of the invention as disclosed in the foregoing and outlined more particularly in the 95 appended claims. I therefore consider such 100 modifications and adaptations as my own.

It will be observed that a lug 34 extends inwardly from the flange 30 and is received within a slot in the outer end of the casing 15, thereby insuring the proper positioning of the inner casing 16 within the latter.

I claim:

1. In a water system, a waste pipe provided with a trap, and a normally closed automatic valve connected with said waste pipe adjacent the junction of the latter with said trap, and opened by suction created by the descent of waste matter through the waste pipe to admit air to the latter, thereby overcomes the suction and preventing syphoning of the water seal from the trap, said valve comprising a tubular outer casing connected at one end with said waste pipe, an inner casing inserted within said outer casing, said inner casing tapering inwardly from its outer end, having its inner end elevated by a lug resting upon the bottom wall of said outer casing, and having apertures formed in its inner end, a circular valve seat held against the outer end of said inner casing, said valve seat being provided with a central opening, a ball valve disposed within the said inner casing, said ball valve being normally moved by force 130

of gravity to the outer end of said inner casing into position to close said opening in the valve seat, and means carried by said inner casing at its inner end to limit the 5 movement of a ball valve in that direction.

2. In a water system, a waste pipe provided with a trap and a normally closed automatic valve operatively connected with said waste pipe and positioned above the 10 level of said trap, said valve comprising a substantially horizontal casing open at its outer end, a circular valve seat, means for

holding said circular valve seat against the outer end of said valve casing, a ball valve disposed within said valve casing and 15 adapted for engagement with said valve seat to close the outer end of said valve casing, and an inclined guide mechanism disposed within said valve casing for normally guiding said ball valve into closed position, 20 whereby said ball valve is normally moved by gravity into closed position and is moved by suction into open position.

EDMOND J. FORTIER.
